C. W. WOOD

ACCELERATOR PEDAL

Filed Jan. 7, 1925

5 INVENTOR
Clarence W. Wood

BY *T. F. Bourne*
ATTORNEY

UNITED STATES PATENT OFFICE.

CLARENCE WAINWRIGHT WOOD, OF NEW YORK, N. Y.

ACCELERATOR PEDAL.

Application filed January 7, 1925. Serial No. 968.

To all whom it may concern:

Be it known that I, CLARENCE WAINWRIGHT Wood, a citizen of the United States, and resident of New York city, in the county 5 of New York and State of New York, have invented certain new and useful Improvements in Accelerator Pedals, of which the following is a specification.

Throttles or valves of carbureters on internal combustion engines, particularly as used 10 on automobiles or motor vehicles, are frequently controlled by pedals called accelerators, against which the sole of an operator's shoe is pressed. A sliding action occurs 15 between the shoe sole and the accelerator with consequent wear on the shoe sole, as well as more or less uneven action of the foot pressure on the accelerator resulting in more or less uneven operation of the 20 throttle.

An object of my invention is to provide the accelerator pedal with a member movably attached thereto, and preferably slideable relatively to the accelerator, upon which 25 member the operator's shoe sole will operate whereby when pressure is applied to said member it will remain in contact with the shoe sole and will move or slide relatively to the accelerator while operating the latter 30 to afford smooth movement of the accelerator, and reduce wear on the shoe sole and fatigue of the operator.

Another object is to pivotally support 35 said member upon the accelerator to have rocking movement thereon in the direction of the length of the operator's foot, a further object being to movably mount said member on the accelerator to have rotary movement relatively to the accelerator 40, whereby operation of the accelerator will be more comfortable and strain on the operator's muscles will be relieved.

My invention comprises novel details of improvement that will be more fully herein- 45 after set forth and then pointed out in the claims.

Reference is to be had to the accompanying drawings, forming a part hereof, wherein—

50 Fig. 1 is a detail sectional view illustrating my improvement in connection with an accelerator pedal;

Fig. 2 is a plan view of my improvement, part of the movable member being omitted;

Fig. 3 is a longitudinal section substantially on line 3, 3, in Fig. 2;

Fig. 4 is a cross section substantially on line 4, 4, in Fig. 3;

Fig. 5 is a section on line 5, 5, in Fig. 4;

Fig. 6 is a detail view, partly in section 60 on line 6, 6, in Fig. 3; and

Fig. 7 illustrates a modification.

Similar numerals of reference indicate corresponding parts in the several views.

The accelerator pedal 1 may be of any 65 usual or desired construction. In Figs 1 to 6 the accelerator comprises a rod 2 slideable longitudinally in a tubular guide 3 having a flange or head 4 that may be suitably secured to the foot-board 5, of a motor 70 car or automobile, with the guide 3 projecting downwardly through said board. The rod 2 may be normally pressed outwardly with a portion above the foot-board 5 by any suitable spring. I have shown a 75 coiled spring 6 within guide 3 bearing against a shoulder 2^a on rod 2 and against a cap or hollow nut 7 secured to the outer end of the guide, the rod having a stop nut 8 at its lower end to engage the cap 7 80 to limit the upward movement of rod 2. The rod 2 may be connected to a carbureter 85 throttle arm 9 by any suitable means, such as by a rod 10 pivotally connected to a bell-crank lever 11, suitably supported and pivotally connected at 12 with the stop nut 8, whereby when the accelerator is depressed 90 the throttle will be operated. The rod 2 may be kept from rotating in any suitable way, as by a flat side 2^b on said rod co-operating with a correspondingly shaped side wall 3^a of guide 3 (Fig. 6). In Fig. 7 the accelerator is in the form of a lever 95 pivotally supported at 13 upon a bracket 14 and pivotally connected at 12 by link 15 with lever 11 for operating the throttle. The foregoing parts are illustrative of 100 throttle controlling means adapted for use in connection with my improvements, although other such means may be used.

My improvement comprises a member 16 slidably mounted upon the accelerator and adapted to be actuated by the operator's foot. A supporting and guiding plate or bar 17 supports the member 16 and is attached to the accelerator. In the example illustrated the member 16 is in box-like 105 form, comprising a top plate 16^a, side walls

16^b and end walls 16^c (Figs. 3 and 4), attached to a bottom plate 18 that is slidably fitted to the guide plate or bar 17. The longitudinal edges 18^a of plate 18 are 5 bent inwardly to cooperate with the corresponding beveled edges 17^b of guide plate 17, whereby plate 18 is slidably guided on plate 17 (Fig. 4). The ends 18^b of plate 18 extend outwardly (as by bending the 10 metal of said plate), to extend along the end walls 16^c of member 16, screws 19 detachably securing said parts together (Fig. 3). Within the member 16 is a spring 20, shown attached at one end to a lug 21, bent 15 from an end 18^b, the spring being attached at its other end to a projection or pin 22 secured to guide plate 17 and extending through a longitudinal slot 23 in plate 18 (Figs. 2 and 3). Spring 20 normally 20 draws plate 18 so that the inner end of slot 23 engages projection 22 to normally locate member 16 on guide plate 17, as shown in Figs. 1, 2, 3 and 7. Member 16 may slide along plate 17 (to the 25 right in Fig. 3), until the outer end of slot 23 engages projection 22 to limit such sliding. By preference a foot piece or pad 24, of rubber or other non-slipping material, is secured upon the surface of member 30 16 to adhere to the operator's shoe sole.

The guide plate 17 may be attached upon the accelerator in any suitable way. I have shown the guide 17 provided with ears 35 spaced apart and receiving a pin 26 in holes in said ears, the pin being supported by the accelerator. By having the pin 26 extend transversely respecting the plane of the operator's foot the member 16 may rock on the pin as a pivot in the plane of said 40 foot, upon the accelerator, which will accommodate said member to the angular position of the foot in different positions of height of the accelerator, which will relieve the operation and reduce fatigue of 45 the operator. The ears 25 may be punched from the metal of plate 17 and bent down or may be separate pieces riveted or screwed to said plate.

I have illustrated a head 27 fitted between 50 the ears 25, receiving the pivot pin 26, and attached to the accelerator by means of the threaded part 28 thereof (Fig. 4). I have also shown a plug 29 within a recess 27^a in head 27, which plug has a threaded reduced stem 29^a passing through a hole in 55 the bottom of head 27 and attached to threaded part 28 (Fig. 4). The plug 29 has a transverse passage 30 for pin 26 (Fig. 60 5), the ends of which passage are widened, whereby the pin may rock laterally in said passage. By the means described the head 27, ears 25, plate 17 and member 16 may 65 have a limited lateral rotary motion relatively to the accelerator, serving to accommodate the operator's foot to the member

16 at various angles, so that the member 16, which will adhere to the operator's shoe sole, may turn axially respecting the accelerator according to the position of the foot relatively thereto. 70

In the form shown in Fig. 7 the part 28 is attached to the pivoted accelerator, whereby the head 27 is carried by said accelerator with the member 16 slidably, rockably and pivotally attached thereto in manner described respecting the slidable accelerator rod 2. 75

In accordance with my invention the movable member 16 being mounted upon the accelerator and the operator's foot being placed upon said member the accelerator 80

may be operated by the foot pressure in the usual way for controlling the carburetor throttle valve. When the foot is pressed upon member 16 the latter will slide relatively to the accelerator in accordance with the downward movement of the foot and the accelerator will be depressed. The sole of the operator's shoe will remain in engagement with member 16 without sliding thereon since the necessary relative movement between the member and the accelerator occurs between said member and the guide plate 17, whereby freedom of action of the accelerator is obtained, the shoe sole does 85 not slide in contact with the accelerator, accuracy of operation of the throttle is increased, and wear on the shoe sole is avoided, and ease with smoothness of driving afforded. 90

The member 16 is relatively large beneath the operator's foot and may be readily reached by the foot when shifting from the brake pedal to the accelerator member. The rocking motion of member 16 under the operator's foot as well as the rotary action of member 16 respecting pin 26 enables the foot to rest comfortably upon and be accommodated to the accelerator member in various positions of driving, and the operator obtains a firm seat for his foot on such member. 100

While I have illustrated a practical embodiment of my invention it will be understood that the same is not limited to the details of construction set forth, as the same may be varied, within the scope of the appended claims, without departing from the spirit of my invention. 115

Having now described my invention what I claim is:

1. A device of the class described comprising an accelerator, and a member slidably carried thereon to be actuated by the foot of an operator, said member being slidably relatively to the accelerator in the direction of tilting movement of the foot in depressing the accelerator. 125

2. A device of the class described comprising an accelerator, a member wholly supported by the accelerator and guided 130

thereon to slide relatively thereto in the direction of tilting movement of a foot upon said member when depressing the accelerator, and means pivotally supporting said member 5 on the accelerator.

3. A device of the class described comprising an accelerator, a guide plate carried by the accelerator, and a member slidably guided upon the guide plate, said member 10 being slidable relatively to the accelerator in the direction of tilting movement of the foot in depressing the accelerator.

4. A device of the class described comprising an accelerator, a guide plate carried 15 by the accelerator, a member slidably guided upon the guide plate, a spring connected with said member, and stop means cooperative with said member, whereby the latter is resiliently retained in a normal 20 position.

5. A device of the class described comprising an accelerator, a guide plate, a slid- 25 able member in box-like form, means slidably guiding said member upon said plate, a stop pin upon the plate, and a spring connecting the stop pin with the member,

said member having a slot receiving the pin, whereby the member will be resiliently re- tained in normal position on the guide plate.

6. A device of the class described com- 30 prising an accelerator, and a member slid- ably and pivotally mounted thereon to rock relative to the accelerator, said member be- ing slidable relatively to the accelerator in the direction of tilting movement of the 35 foot in depressing the accelerator.

7. A device of the class described com- 40 prising an accelerator, a member rotatively mounted thereon to have lateral rotary movement relatively to the accelerator, and means to limit lateral rotation in opposite 45 directions of said member relatively to the accelerator.

8. A device of the class described com- 45 prising a guide plate, a member slidably guided thereon, resilient means retaining the member in a normal position, said guide plate having ears, a head pivotally attached to said ears, and means for attaching said head to the accelerator.

CLARENCE WAINWRIGHT WOOD.
